ABDOMINAL REDUCER

Adrienne Shatto and Albert Jardot,
New York, N. Y.

Application June 15, 1936, Serial No. 85,356

2 Claims. (Cl. 272—57)

The present invention relates to a new and improved abdominal reducer.

The primary object of the invention is the provision of a simple apparatus that when applied to the abdomen will serve as a means for reducing excess weight and also to strengthen the muscular region surrounding the abdomen.

The invention will be fully and comprehensively understood from a consideration of the following detailed description when read in connection with the accompanying drawing which forms part of the application.

In the drawing:

Fig. 1 is a perspective view of the device.

Fig. 2 is a front elevational view;

Fig. 3 is a bottom plan view of the device illustrating the means for connecting the several parts; and

Fig. 4 is a cross sectional view on the line 4—4 of Fig. 3.

Referring to the drawing for a more detailed description thereof, the apparatus is indicated generally by the numeral 5 and comprises a reducer consisting of a plurality of weight sections, each being detachable from the other. For purposes of illustration there are disclosed three sections 6, 7 and 8, respectively. It is to be understood, however, that a greater or lesser number of sections may be provided to change the mass of the reducer without departing from the spirit of the invention. Each section is formed preferably of metal or similar material and may be suitably finished to render an attractive appearance.

The outer surface of each section is convexed and the inner surface concaved so that, when connected, the several sections will conform to the general shape of the abdomen. The sections are connected by means of pintle pins 9 which extend thru hinge means 9' formed in the concaved surface of each section, the pin passing thru the interconnected part forming the hinge.

The means for attaching the reduced to the body includes looped members 10 and 11 which extend from the outer sections 6 and 8, respectively, with a belt or other fastening means 12 engaged therein, said belt being adapted to pass around the body of the wearer. The belt is adjustable, whereby the device is applicable for persons of various weights.

Additional loops 13 and 14 are also provided on the upper portion of the outer sections 6 and 8, to which is attached a handle 15, and the purpose thereof is to change the position of the reducer by grasping said handle and moving from one position to another on the abdomen.

In the use of the apparatus, the person ap-

plying the same assumes a supine reclining position and the concaved portion of the reducer is placed on the abdomen. The constant application of the reducer to the desired parts of the body, and the weight thereof, tends to reduce excess weight and at the same time strengthen the muscular regions surrounding the abdomen. By grasping the handle 15, the reducer can be readily moved to various positions, thereby effecting a reducing of excess weight around the complete area of the abdomen.

It is to be understood that this improvement is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed as new is:

1. A reducing appliance to be applied and operated upon the abdominal region of the body of a person in a supine reclining position, said appliance comprising a unitary articulate sectional body element of substantial weight, said element as a combined unit being concaved longitudinally and transversely throughout its inner side which is made to supportingly contact the adjacent underlying portion of the body of the user, and an attaching belt secured to the opposite ends of the said weighted body element and adapted to substantially encircle the adjacent body portion of the user whereby to attach the weighted element with freedom of positioning and manipulating movement.

2. The herein described reducing appliance comprising a unitary articulate sectional body element of substantial weight, the sections of which are detachably joined by transverse hinged connections adjacent their inner sides which supportingly engage the adjacent underlying portions of the body of the user, said inner side portions of the sections being concaved in continuity from end to end and transversely of said weighted element as a unit and the unit being roundly convexed on its outer side throughout the length and breadth thereof, an adjustable attaching strap secured to the opposite end sections of said weighted body element and adapted to substantially encircle the body of the user whereby to attach the appliance with freedom of positioning and manipulating movement of said weighted element thereof, and handle means on said weighted element for effecting the positioning adjustment and manipulative movement of said element.
